UNITED STATES PATENT OFFICE.

WILLIAM B. STANLEY, OF TIFFIN, OHIO.

POST-PROTECTOR.

SPECIFICATION forming part of Letters Patent No. 761,721, dated June 7, 1904.

Application filed December 21, 1903. Serial No. 186,105. (No model.)

To all whom it may concern:

Be it known that I, WILLIAM B. STANLEY, a citizen of the United States, residing at Tiffin, in the county of Seneca and State of Ohio, have invented a new and useful Post-Protector, of which the following is a specification.

This invention relates to devices for the protection from fire of telegraph, telephone, and similar poles, signal-posts, line or feed wire posts, trolley - line - conductor posts, fence-posts, and the like, and has for its object to simplify and improve the construction and produce a device of this character which may be adapted to any form or size of post of combustible material which requires protection from fire.

The device may be employed upon posts of various kinds erected adjacent to railway-lines which are liable to be affected by burning grass or other growth which has been ignited from locomotive-sparks or from other causes and may also be employed to advantage for the protection of farm-fence posts in localities liable to be affected by prairie-fires and the like.

For the purpose of illustration the device is shown in Figure 1 applied to an ordinary telegraph or telephone pole, and in Fig. 2 applied to an ordinary fence-post. Fig. 3 represents the two parts comprising the improved device partially united to illustrate the manner of installing them upon the post. Fig. 4 represents an end elevation of the improved device with the post in transverse section. Fig. 5 is an enlarged sectional detail illustrating the manner of forming and attaching the fence-wire clips. Fig. 6 is a view similar to Fig. 4, showing the device formed of cement, burned clay, or similar material or compounds.

The improved device comprises two parti-cylindrical members 10 11, each greater than one-half of a complete cylinder and adapted to be united around the post 12 by sliding one member longitudinally upon the other, with the edges of the members interlapping, as shown in Figs. 4 and 6. When thus assembled, it will be obvious the two parts are firmly locked from lateral movement and can be separated only by longitudinal movement of one of the members relative to the other, as illustrated in Fig. 3.

The material employed for the parts 10 11 may be of any suitable non-combustible substance or composition, such as sheet, metal, clay, burned or dried, concrete or other cement compounds, and the like.

In Fig. 4 the parts are represented as constructed of sheet metal, while in Fig. 6 a pair of the members are shown as formed of cement or similar compounds. By this simple arrangement it will be evident that a very effective protection for the post is provided which may be cheaply constructed, quickly applied, and may be adapted to all sizes of posts and to posts employed for any purpose.

It is obvious that the protecting members must be made of ample size to include between them the post which is to be protected, and it is equally obvious that the larger of the two members must necessarily be of an interior diameter exceeding the exterior diameter of the post. An intermediate opening or air-space is thus formed between the protecting members and the post which efficiently aids in attaining the objects of the invention.

The lower ends of the members 10 11 may be embedded for a distance in the ground (represented at 13) as a further protection to the posts.

When employed as a protector for fence-posts, one of the casing members will be provided with a plurality of clips 14, spaced apart for supporting the lower strand-wires 15 of the fence, the upper strand-wires 16 being supported in the usual manner upon the post above the protector, as shown.

The manner of connecting the strand-wire clips is shown in Fig. 5.

Having thus described the invention, what I claim is—

A post-protecting device consisting of two parti-cylindrical members, each greater than one-half and one of said members being of an exterior diameter equal to the interior diameter of the other member.

In testimony that I claim the foregoing as my own I have hereto affixed my signature in the presence of two witnesses.

WILLIAM B. STANLEY.
